UNITED STATES PATENT OFFICE

2,437,658

INTERENGAGING IMPELLER TYPE BLOWER
OR PUMP

Alfred O. Williams, Battle Creek, Mich.

Application January 21, 1944, Serial No. 519,107

11 Claims. (Cl. 230—141)

1

This invention relates to improvements in interengaging impeller type blower or pump.

The main objects of this invention are:

First, to provide a blower or pump well adapted for air and other fluids which is of substantial capacity and adapted to deliver fluid under substantial pressure.

Second, to provide a structure having these advantages in which no packings for the impellers are required other than such as may be desirable for the impeller shafts.

Third, to provide a structure having these advantages in which the impellers may be readily machined and assembled in coacting abutment forming relation.

Further objects pertaining to details and economies of the invention will definitely appear from the description to follow. The invention is defined in the claims.

A structure which embodies the features of the invention is clearly illustrated in the accompanying drawing, in which:

Fig. 1 is a fragmentary view partially in section of a pump or blower embodying the features of the invention, certain of the parts being shown conventionally and only such parts being illustrated as are deemed desirable for an understanding of a practical embodiment of the invention.

Fig. 2 is a fragmentary view partially in section showing the impellers in another position in their cycle of movement from that shown in Fig. 1.

Fig. 3 is a fragmentary view partially in section corresponding to that of Figs. 1 and 2, showing the impellers in another position in their cycle of movement.

Fig. 4 is a fragmentary view partially in section showing a slightly modified form or embodiment of the invention.

Fig. 5 is a fragmentary view partially in section showing the impellers at another position in their cycle of movement.

Fig. 6 is a fragmentary view partially in section showing the impellers in still another position in their cycle of movement.

In the embodiment of the invention shown in Fig. 1 the casing designated generally by the numeral 1 is provided with an inlet 2 and with an outlet 3. This casing is provided with or comprises lobes 4, 5 and 6 having cylindrically curved

2

side walls, the first and second lobes 4 and 5 being arranged in side by side relation and the third lobe 6 being arranged in opposed relation. The curves of the walls of the first and second lobes intersect at 7 while the curve of the third lobe and the second lobe intersect at 8. The lobe 4 is open to the inlet 2 as is also the lobe 6.

In the embodiment shown in Figs. 1 to 3 the outlet 3 is formed in the end wall 9 of the third lobe 6 and this lobe has a recess 10 in its peripheral wall adjacent the outlet and in communication therewith when the impellers are in position so that the compressed fluid is being discharged.

I provide first, second and third impellers designated 11, 12 and 13, respectively. It will be understood that the terms "first," "second" and "third" lobes and "first," "second" and "third" impellers are used largely as a matter of convenience in description and designation of parts. The shafts

14, 15 and 16 of the impellers 11, 12 and 13 are driven synchronously, the shafts 14 and 15 being driven in the same direction of rotation and the shaft 16 in the opposite direction of rotation. The driving connections are conventionally illustrated, the driving gear 17 being in mesh with the gears 18 and 19 of the shafts 14 and 15, while the gear 20 of the shaft 16 is in mesh with the gear 19. The shafts are driven at the same speed.

The impellers or rotors 11 and 12 are of general elliptical shape having curved sides 21 terminating in relatively pointed ends 22 which constitute the ends of the vanes of the impellers. These ends are, however, preferably curved in a small arc.

35 The impeller 13 has oppositely disposed lobes 23 having curved outer ends 24, these lobes constituting the vanes of this impeller 13. Recesses 25 are formed between the lobes or the curved surfaces of the lobes. The impellers 11 and 12

40 are so proportioned and their curvature is such that they are at all times in coacting abutment forming relation. The curved ends of the lobes 23 of the impeller 13 are of such dimensions and curvature and the impeller 12 is of such dimensions and curvature that the impellers 12 and 13 are at substantially all times in coacting abutment forming relation. The recesses 25 are such as to receive the ends of the impeller 12.

In the embodiment shown in Figs. 4, 5 and 6

50 the outlet 26 opens into the second lobe 5 and

the final compression is in the lobe 5. In the embodiment shown in Fig. 1 the final compression and delivery is mainly in the lobe 6. A delivery pipe 21, as shown in Fig. 1, may be provided with a return check valve 28. A similar check valve 29 is provided in the embodiment shown in Fig. 4.

With the parts thus arranged the rotation of the first impeller 11 traps air in the first lobe 4, delivering it into the second lobe 5, the impellers being shown in Figs. 3, 1 and 2 in successive positions of their cycle of movement. In Fig. 3 the impellers are shown with the first impeller in air entrapping position and the second impeller in air compressing position, and in Fig. 1 in a further air compressing and delivery position. In Fig. 2 the impeller 11 is shown in position to deliver its charge into the second lobe, where it is picked up by the second impeller 12 and compressed and delivered to the outlet as described. The impeller 13 traps air from the inlet when in approximately the position shown in Fig. 2. This trapped air is also conveyed to the delivery. Inasmuch as the space for the trapped air is constantly decreased through each cycle of movement from the initial trapping of the air, a substantial compression of the confined or trapped air results. The embodiment shown in Figs. 1 to 3 has a somewhat greater capacity for air compression than the embodiment shown in Fig. 4, although the degree of compression depends largely on the head on which the air is delivered.

I have indicated by arrows the direction of rotation of the impellers, the first and second impellers 11 and 12 being rotated in clockwise direction while the third impeller 13 is rotated in counterclockwise direction. The flow of fluid is indicated by dotted lines.

I have illustrated and described the invention in practical embodiments thereof. I have not attempted to illustrate various structural details in arrangement of driving gears and the like as it is believed this disclosure will enable those skilled in the art to embody or adapt my invention as may be desired.

Having thus described my invention, what I claim as new and desire to secure by Letters Patent is:

1. In a blower, the combination of a casing having an inlet and an outlet and comprising first and second lobes disposed side by side with the first lobe opening to said inlet and a third lobe disposed in opposed relation to the first and second lobes and opening to the inlet, said lobes having end walls and cylindrically curved side walls, the curved side walls of the first and second lobes intersecting each other, the curve of the side wall of the third lobe intersecting the curve of the side wall of the second lobe, the outlet being in an end wall of the third lobe, the side wall of the third lobe having a recess therein adjacent the outlet, first and second impellers disposed within and coacting with the first and second lobes respectively and synchronously driven for rotation in the same direction, said first and second impellers having symmetrically curved sides and terminating in substantially pointed ends and being in coacting abutment relation to each other, and a third impeller disposed within and coacting with the third lobe and synchronously driven with said first and second impellers in the opposite direction relative to the direction of rotation of said first and second impellers, said third impeller having opposed lobes with curved ends and side recesses between the lobes, said second and third impellers being in coacting abutment relation with the side recesses of the third impeller receiving the ends of the second impeller.

2. In a blower, the combination of a casing having an inlet and an outlet and comprising first and second lobes disposed side by side with the first lobe opening to said inlet and a third lobe disposed in opposed relation to the first and second lobes and opening to the inlet, said lobes

10 having end walls and cylindrically curved side walls, the curved side walls of the first and second lobes intersecting each other, the curve of the side wall of the third lobe intersecting the curve of the side wall of the second lobe, the outlet being in an end wall of the third lobe, first and second impellers disposed within and coacting with the first and second lobes respectively and synchronously driven for rotation in the same direction, said first and second impellers having symmetrically curved sides and terminating in substantially pointed ends and being in coacting abutment relation to each other, and a third impeller disposed within and coacting with the third lobe and synchronously driven with said first and second impellers in the opposite direction relative to the direction of rotation of said first and second impellers, said third impeller having opposed lobes with curved ends and side recesses between the lobes, said second and third impellers being in coacting abutment relation with the side recesses of the third impeller receiving the ends of the second impeller.

3. In a blower, the combination of a casing having an inlet and an outlet and comprising first and second lobes disposed side by side with the first lobe opening to said inlet and a third lobe disposed in opposed relation to the first and second lobes and opening to the inlet, said lobes having cylindrically curved side walls, the curved side walls of the first and second lobes intersecting each other, the curve of the side walls of the third lobe intersecting the curve of the side wall of the second lobe, first and second impellers disposed within and coacting with the first and second lobes respectively and synchronously driven for rotation in the same direction, said first and second impellers having symmetrically curved sides and terminating in substantially pointed ends and being in coacting abutment relation to each other, and a third impeller disposed within and coacting with the third lobe and synchronously driven with said first and second impellers in the opposite direction relative to the direction of rotation of said first and second impellers, said third impeller having opposed lobes with curved ends and side recesses between the lobes, said second and third impellers being in coacting abutment relation with the side recesses of the third impeller receiving the ends of the second impeller.

4. In a blower, the combination of a casing having an inlet and an outlet and comprising first and second lobes disposed side by side with the first lobe opening to said inlet and a third lobe disposed in opposed relation to the first and second lobes and opening to the inlet, first and second impellers disposed within and coacting with the first and second lobes respectively and synchronously driven for rotation in the same direction, said first and second impellers having symmetrically curved sides and terminating in substantially pointed ends and being in coacting abutment relation to each other, and a third impeller disposed within and coacting with the third lobe and synchronously driven with said

first and second impellers in the opposite direction relative to the direction of rotation of said first and second impellers, said third impeller having opposed lobes with curved ends and side recesses between the lobes, said second and third impellers being in coacting abutment relation with the side recesses of the third impeller receiving the ends of the second impeller.

5. In a blower, the combination of a casing having an inlet and an outlet and comprising first and second lobes disposed side by side with the first lobe opening to said inlet and a third lobe disposed in opposed relation to the first and second lobes and opening to the inlet, said lobes having end walls and cylindrically curved side walls, the curved side walls of the first and second lobes intersecting each other, the curve of the side wall of the third lobe intersecting the curve of the side wall of the second lobe, the outlet being in an end wall of the third lobe, the side wall of the third lobe having a recess therein adjacent the outlet, first and second impellers disposed within and coacting with the first and second lobes respectively and synchronously driven for rotation in the same direction and being in coacting abutment relation to each other, and a third impeller disposed within and coacting with the third lobe and synchronously driven with said first and second impellers in the opposite direction relative to the direction of rotation of said first and second impellers, said second and third impellers being in coacting abutment relation.

6. In a blower, the combination of a casing having an inlet and an outlet and comprising first and second lobes disposed side by side with the first lobe opening to said inlet and a third lobe disposed in opposed relation to the first and second lobes and opening to the inlet, said lobes having end walls and cylindrically curved side walls, the curved side walls of the first and second lobes intersecting each other, the curve of the side wall of the third lobe intersecting the curve of the side wall of the second lobe, the outlet being in an end wall of the third lobe, first and second impellers disposed within and coacting with the first and second lobes respectively and synchronously driven for rotation in the same direction and being in coacting abutment relation to each other, and a third impeller disposed within and coacting with the third lobe and synchronously driven with said first and second impellers in the opposite direction relative to the direction of rotation of said first and second impellers, said second and third impellers being in coacting abutment relation.

7. In a blower, the combination of a casing having an inlet and an outlet and comprising first and second lobes disposed side by side with the first lobe opening to said inlet and a third lobe disposed in opposed relation to the first and second lobes and opening to the inlet, said lobes having cylindrically curved side walls, the curved side walls of the first and second lobes intersecting each other, the curve of the side wall of the third lobe intersecting the curve of the side wall of the second lobe, first and second impellers disposed within and coacting with the first and second lobes respectively and synchronously driven for rotation in the same direction and being in coacting abutment relation to each other, and a third impeller disposed within and coacting with the third lobe and synchronously driven with said first and second impellers in the opposite direction relative to the direction of rotation of said first and second impellers, said second and third impellers being in coacting abutment relation.

tation of said first and second impeller, said second and third impellers being in coacting abutment relation.

8. In a blower, the combination of a casing having an inlet and an outlet and comprising first and second lobes disposed side by side with the first lobe opening to said inlet and a third lobe disposed in opposed relation to the first and second lobes and opening to the inlet, first and second impellers disposed within and coacting with the first and second lobes respectively and synchronously driven for rotation in the same direction and being in continuous coacting abutment relation to each other to impel the fluid from the inlet towards the outlet, and a third impeller disposed within and coacting with the third lobe and synchronously driven with said first and second impellers in the opposite direction relative to the direction of rotation of said first and second impellers, said second and third impellers being in continuous coacting abutment relation relative to each other.

9. In a blower, the combination of a casing having an inlet and an outlet and comprising first and second lobes disposed side by side with the first lobe opening to said inlet and the second communicating with the outlet and a third lobe disposed in opposed relation to the first and second lobes and opening to the inlet, first and second impellers disposed within and coacting with the first and second lobes respectively and synchronously driven for rotation in the same direction and being in continuous coacting abutment relation relative to each other to impel the fluid from the inlet towards the outlet, and a third impeller disposed within and coacting with the third lobe and synchronously driven with said first and second impellers in the opposite direction relative to the direction of rotation of said first and second impellers, said second and third impellers being in continuous coacting abutment relation relative to each other.

10. In a blower, the combination of a casing having an inlet and an outlet and comprising first and second lobes disposed side by side with the first lobe opening to the inlet, and a third lobe disposed in opposed relation to the first and second lobes and opening to the inlet, first and second impellers disposed within and coacting with the first and second lobes respectively and synchronously driven for rotation in the same direction, the first and second impellers having symmetrically curved sides defining symmetrically shaped relatively pointed ends constituting tapered vanes and being in coacting abutment relation to each other, and a third impeller disposed within and coacting with the third lobe and synchronously driven with the first and second impellers but in the opposite direction relative to the direction of rotation of said first and second impellers, said third impeller having opposed lobes with curved ends and side recesses between the lobes, one of said first mentioned impellers being in coacting abutment relation with the third impeller.

11. In a blower, the combination of a casing having an inlet and an outlet and comprising first and second lobes disposed side by side with the first lobe opening to the inlet, and a third lobe disposed in opposed relation to the first and second lobes and opening to the inlet, first and second impellers disposed within and coacting with the first and second lobes respectively and synchronously driven for rotation in the same direction, the first and second impellers being in coacting abutment relation to each other, and a third impeller disposed within and coacting with the third lobe and synchronously driven with the first and second impellers in the opposite direction relative to the direction of rotation of said first and second impellers, said second and third impellers being in coacting abutment relation.

continuous coaxing abutment relation to each other to impel the fluid from the inlet towards the outlet, and a third impeller disposed within and coaxing with the third lobe and synchronously driven with the first and second impellers but in the opposite direction relative to the direction of rotation of said first and second impellers, one of said first mentioned impellers being in continuous coaxing abutment relation with the third impeller.

ALFRED O. WILLIAMS.
